3,226,806 METHOD OF MAKING A CATHODE HEATER ASSEMBLY

Clyde Robert Gatewood, San Francisco, Calif., assignor
to Eitel-McCullough, Inc., San Carlos, Calif., a corpora-
tion of California
Filed Mar. 18, 1960, Ser. No. 16,026
7 Claims. (Cl. 29—155.62)

This invention relates to cathode-heater assemblies for electron tubes, and particularly to a wire-wound heater coil for indirectly heated cathodes, the heater coil being embedded in insulating material.

In the electronics industry, it has been a continuing problem to adequately support separate and generally close-spaced elements which make up an electronic component, such as an electron gun. Experience has taught that extremes in temperature, shock, and vibration tend to disrupt operation of electronic components due to rupture or displacement of such closely spaced elements. Thus, in an electron tube using an indirectly heated cathode heated by a cathode heater coil, shock and vibration may result in rupture of the resistance wire forming the coil, thus causing failure of the tube. Instead of being ruptured the heater coil elements may be displaced, thus bringing them into shorting contact with each other or surrounding structure. This is equally detrimental to operation of the tube, and it is therefore one of the objects of the invention to provide means for rigidly supporting a cathode-heater assembly.

The prior art discloses that attempts have been made to rigidly support heating elements and cathode heater coils by embedding or coating such elements and coils in various dielectric materials applied by various methods. Almost invariably such coatings and embedding materials have been found to chip and crack, forming fissures which often destroy the effectiveness of the coating. It is consequently another object of the invention to provide a wire-wound heater element embedded in insulating material, such as alumina, in a manner which precludes chipping and cracking of the alumina due to differences in thermal expansion and contraction of the different materials.

For maximum cathode and heater efficiency, it is important that the heater coil follow the contour of the cathode. Any material deviation from this conformation causes concentrations of heat in different areas of the cathode, resulting in irregular emission of electrons from the overheated areas. This is particularly true as regards cathodes designed for beam tube applications. It is therefore still another object of the invention to provide a heater coil shaped to conform to the cathode with which it is associated, and which is embedded in insulating material which similarly conforms to the shape of the cathode.

It is also desirable that the heater coil have maximum thermal conductivity with relation to the cathode in order that a maximum uniform cathode temperature in minimum time will be provided. Such thermal conductivity is best obtained by placing the heater coil as close as possible and contiguous to the cathode. However, it is also necessary that the heater coil be electrically insulated intermediate its ends from the cathode. Thus, to provide good thermal conductivity between heater coil and cathode, it has been found preferable to provide as thin a section of electrical insulation between the heater coil and the cathode as is practicable. It is therefore a still further object of the invention to provide a heater coil embedded in dielectric material in a manner to provide a surface layer of dielectric material on each side of the heater coil, the surface layer on the cathode side of the coil being inner than the surface layer on the other side of the coil. Still another object of the invention is the provision of

a method for embedding heater coils in thermally conductive material having high dielectric strength.

A still further object of the invention is the provision of a cathode-heater assembly for beam tubes, the cathode being dish-shaped and the heater coil being embedded in dielectric material in a manner to provide an annular wafer conforming to the curvature of the dish-shaped cathode.

Another object is the provision of a method of embedding a heating coil having a spheroidal conformation in a wafer of dielectric material conforming to the curvature of the heating coil.

The invention possesses other objects and features of advantage, some of which, with the foregoing, will be set forth in the following description of the invention. It is to be understood that the invention is not limited to the embodiment disclosed, as variant embodiments may be adopted within the scope of the appended claims.

The problems indicated above have been obviated by the cathode-heater assembly forming the subject matter of this invention. For purposes of clarity in the description, the invention will be described as embodied in unipotential-type cathode-heater assemblies, particularly adapted for use in the electron guns of beam tubes. It will, of course, be understood that the invention is applicable to other type cathode-heater assemblies.

Broadly considered, the cathode-heater assembly forming the subject matter of the invention comprises, in the embodiment chosen for illustration, a dish-shaped cathode operatively supported in close proximity to a spirally wound heater coil. The heater coil is provided with dielectric means bonded to the spiral windings and forming electrical insulation between the cathode and the windings and mechanical support therefor. In its preferred form, the spiral windings of the heater coil are axially displaced in increasing increments to provide the heater coil with a spheroidal conformation corresponding to the curvature of the dish-shaped cathode with which it is associated. The dielectric material, applied in molten form by flame-spraying, immediately hardens and effectively retains the heater windings in their spheroidal conformation. Appropriate electrical leads connect the heater coil to a source of power, and suitable shield means are provided to reflect or re-direct heat from the coil back toward the cathode for maximum efficiency. Means are also provided cooperating with the shield means to retain the cathode and heater in a rigid vibration-free relationship possessing maximum heat exchanging efficiency.

Referring to the drawings:

FIGURE 1 is a vertical half-sectional view showing the cathode-heater assembly mounted on an appropriate support, the support being shown in dash lines. A portion of the cathode-heater assembly is broken away to reduce the size of the figure.

FIGURE 2 is a side elevation of the heater coil shown as initially wound with the spiral windings lying in planar alignment.

FIGURE 3 is a plan view of the spirally wound heater coil of FIGURE 2, showing the spacing between the individual windings of the coil.

FIGURE 4 is a transverse sectional view of the heater coil after the windings have been axially displaced to provide a spheroidal conformation, and showing the windings embedded in an annular wafer of dielectric material.

FIGURE 5 is a plan view of the annular wafer shown in FIGURE 4.

FIGURE 1 is shown approximately twice actual size, and FIGURES 2, 3, 4, and 5 are shown approximately 1½ times actual size.

In greater detail and referring to FIGURE 1 of the drawing, the cathode-heater assembly of my invention is shown embodied in a unipotential matrix-type cathode 2,

3

having a concave emitting surface 3 and a convex non-emitting surface 4. In the embodiment shown, the cathode is suitably secured to a cathode ring 6 having a radially extending flange 7 and a peripheral cylindrical flange 8. The cathode ring flange 7 is suitably secured, as by welding or brazing, to the associated outer peripheral portion of the cathode. Cylindrical flange 8 on the cathode ring is suitably welded or brazed to the inner free end of a hollow cylindrical shell 9 forming a support for the cathode and a heat dam to prevent conduction of heat away from the cathode.

The outer end of the heat dam shell is integrally united to the inner end of a hollow cylindrical support shell 12 having apertures 13 circumferentially spaced therearound intermediate its ends to reduce the cross-sectional area of the shell to restrict the flow of heat therethrough. The outer end of shell 12 nests around the cylindrical portion 14 formed on the inner end of hollow conical support shell 16. The union 17 between cylindrical shell 12 and conical shell 16, while shown as being a brazed or welded joint in FIGURE 1, may obviously be a continuous one-piece construction if desired. To rigidly secure the cathode within the tube envelope, radially extending integral base flange 18 on the outer end of the conical shell 16, is suitably brazed to the inner surface of the envelope wall portion 19, shown in dash lines in FIGURE 1. To restrict the conduction of heat away from the cathode, the cylindrical shell 12 and conical shell 16 are preferably fabricated from very thin gauge material. Nickel and Kovar have been found to possess the requisite thermal characteristics and to retain the desired structural rigidity even at the elevated temperatures at which the cathode operates.

To heat the cathode to the desired operating temperature, a heating coil 20 is provided. The coil is formed from a length of resistance wire 21, conveniently tungsten or platinum, doubled to form a bight 22 so that parallel conductors are provided joined at the bight, and with terminal leads 23 at their ends lying closely adjacent each other. The doubled resistance wire is then spirally wound so that spaced windings in planar alignment are provided. As best seen in FIGURE 3, the bight 22 is arranged adjacent the outer periphery of the coil, and the coil is spirally wound so that at its inner periphery the two adjacent ends of the resistance wire form the terminal leads 23. Alternatively, the bight 22 can be arranged adjacent the inner periphery of the coil and the coil spirally wound outwardly in order to place the terminal leads 23 near the outer periphery of the coil.

In order to displace the windings to provide a spheroidal conformation corresponding to the convex curvature of the cathode 2, the coil is mounted in a suitable jig (not shown) and the windings are axially displaced varying amounts or in increasing increments commencing from the outer periphery of the coil and ending at the inner periphery. While retained in this position on the jig, the coil is flame-sprayed with molten ceramic material, preferably high dielectric strength alumina, the dielectric material hardening into an annular electrically insulating and mechanically rigid supporting wafer 24.

To retain the coil windings in their proper relationship while they are being sprayed with dielectric material, a platen (not shown) similar in conformation to the curvature of the cathode surface with which the coil will ultimately be associated, is pressed downwardly on the coil and depresses the separate windings of the coil the proper amount to provide the desired spheroidal conformation. The coil is then flame-sprayed with ceramic material to retain the coil windings in position. Alternatively, the windings while in planar alignment, as shown in FIGURES 2 and 3, may be given a light coating of flame-sprayed ceramic material and the light coating permitted to harden. The lightly coated coil is then pressed into the desired spheroidal conformation as previously explained. At this point each of the windings will be

10 found to be surrounded by a thin layer of hardened ceramic material, in the order of about .010 inch thick.

15 It has been found that displacing the windings to form a spheroidal conformation does not crack nor chip the thin coating of ceramic material. Once having displaced the lightly coated windings to the desired curvature, the coil is again flame-sprayed with molten ceramic material from the side opposite the platen which holds the coil in position. This results in a thicker coating of ceramic material being built up on the back or convex side of the coil, while a relatively thinner layer of ceramic material covers the coil windings on the concave side of the coil. This condition is best shown in FIGURE 1. When the spaced windings are sprayed with molten dielectric material, the dielectric material builds up on the surface of the wire, forming a depression in the space between the windings. If desired, spraying may be continued until these depressions are substantially filled on the back or convex side of the coil; however, on the concave side it is desirable that the depressions be permitted to remain. It has been found that on the concave side of the heater coil it is desirable that the ceramic coating interposed between the coil windings and the underside of the cathode be as thin as possible. This places the heater windings as close to the convex surface 4 of the cathode as is practicable, there being only a .010 inch thickness of dielectric material separating the windings from the cathode. It will thus be seen that the layer of dielectric material functions in the manner of a manifold to evenly distribute heat from the heater windings and efficiently conduct it to the cathode by reason of its contiguous relation thereto. Radiation of heat from the depressions aids in providing a uniform temperature throughout the cathode.

20 Forming the ceramic wafer in this manner precludes cracking or chipping due to differences in expansion and contraction between the ceramic and the heater coils. This result has not been achieved where the ceramic in a plastic state is cold-sprayed or cast around the heater windings and then fired to harden. In the latter case it has been found that when the heater windings are subsequently heated, the differences in expansion and contraction result in cracking and destruction of the ceramic wafer. The reason why the ceramic coating of my invention is not affected in this way is believed to be due to the phenomenon that when the molten ceramic is flame-sprayed onto the heater windings, the heat from the molten ceramic causes the wire to expand. The ceramic material is also expanded because of its molten condition, but upon cooling after being sprayed, it cools faster than the wire which it surrounds. The ceramic having cooled and hardened and therefore being possessed of some dimensional stability, the wire contained within the ceramic then slowly cools and is believed to contract and shrink, stressing the bond between the embedded resistance wire and the surrounding dielectric material. In some instances the resistance wire may contract sufficiently to form a void between the wire and the surrounding dielectric material. When the heating element is subsequently heated by passing an electric current therethrough, the thermal expansion of the wire merely relieves the stress on the bond or fills the void if such there be. When maximum expansion of the wire has been achieved, it is believed the tensile stress imposed on the ceramic wafer is well below the destructive value that would normally be imposed if the stress in the bond did not have to be overcome or if a slight void did not exist. It will thus be seen that the ceramic material is stressed much less than it would be if the ceramic in a plastic state were cold-sprayed or cast about the cold heater windings.

25 30 35 40 45 50 55 60 65 70 75 Means are provided to secure the embedded heater coil in operative position beneath the convex surface of the cathode. Fitting snugly over each terminal lead 23 is a ceramic bushing 26 having a flange 27 at its upper end abutting the under surface 28 of the dielectric wafe adjacent its inner periphery. Fitting snugly about the

main body portions 26 of the bushings are a plurality of dish-shaped heat shields 29 substantially complementary to the shape of the cathode. Each of the heat shields is provided with an aperture through which the body portion 26 of the bushing extends, and each is additionally provided with a plurality of dimples 31, shown best in FIGURE 1. The dimples serve to space the heat shields one above the other in operating position under the cathode. To support the heater coil and heat shields in operating position a bottom support shield 32 is provided. This shield is substantially similar to the heat shields 29; however, it is additionally provided with a peripheral cylindrical flange 33 welded or brazed to the cylindrical support shell 9, which functions as a heat dam to inhibit the flow of heat away from the cathode. It will thus be seen that the embedded heater coil together with the heat shields 29, lie caught between the bottom surface of the cathode 2 and the upper concave surface of the bottom support shield 32. This construction effectively retains the parts against movement due to vibration and shock, and also retains the heat in the cathode area to provide maximum efficiency.

To energize the heater coil, one of the terminal leads 23 extends downwardly and is integrally and hermetically brazed in the upper end of a conductive sleeve 36 which continues downwardly and extends out of the envelope through the support plate 19, to be connected to a source of power to pass a heating current through the coil. To complete a conductive circuit through the heating coil, the other terminal 23 is welded to one end of strip conductor 37, which at its other end is welded to the flange 33 on the support shield 32. Support shell 12 and conical shell 16 complete the circuit.

From the foregoing it will be obvious that an efficient and rigid cathode-heater assembly has been provided. The individual parts are designed for facility of fabrication, and after fabrication the parts cooperate to provide a vibration-free structure. Such vibration-free construction ensures long and efficient life for the cathode-heater assembly.

I claim:

1. The method of fabricating a heater coil for electron tubes comprising winding a length of resistance wire to provide spaced windings in planar alignment, displacing selected windings in varying increments to provide said coil with a spheroidal conformation, and depositing molten dielectric material on said windings while so displaced to form a dielectric coating thereon to electrically insulate and mechanically support said windings.

2. The method of fabricating a heater coil for electron tubes comprising spirally winding a length of resistance wire to provide a multiplicity of radially spaced spiral windings in planar alignment, axially displacing adjacent windings in varying increments to provide said coil with a spheroidal conformation, and embedding said windings in a dielectric material while so displaced to electrically in-

sulate and mechanically support said coil windings in said spheroidal conformation.

3. The method according to claim 2, in which said dielectric material comprises alumina, and said windings are embedded by spraying molten alumina thereon.

4. The method of making an electric heater for electron tubes comprising the steps of placing a thin coating of dielectric material in molten form on resistance wire, allowing said coating to harden, forming said wire into a desired shape having spaced adjacent turns, and then placing a second coating of dielectric material in molten form on the precoated and formed structure, said second coating being applied in sufficient quantity to fill the spaces between said turns and thereby hold the wire in said desired shape.

5. The method according to claim 4, in which said thin coating is applied to the entire periphery of said wire, said final desired shape is obtained by pressing the wire against a platen, and said second coating is applied to the wire from the side of the wire opposite said platen.

6. The method according to claim 4 in which the wire is formed into a shape approximating said desired shape prior to applying said thin coating, said approximate shape having spaced adjacent turns, and said thin coating being applied in insufficient quantity to interconnect said turns.

7. The method according to claim 6 in which said desired shape is obtained by pressing the wire against a spheroidal platen, and said second coating is applied to form a greater thickness of dielectric material on the convex side of the heater.
